UNITED STATES PATENT OFFICE.

JACOB C. MILLER, OF MILWAUKEE, WISCONSIN.

CUSHIONED VALVE TAPPET.

Application filed November 20, 1923. Serial No. 675,821.

To all whom it may concern:

Be it known that I, JACOB C. MILLER, a citizen of the United States, and a resident of the city of Milwaukee, in the county of Milwaukee and State of Wisconsin, have invented certain new and useful Improvements in Cushioned Valve Tappets; and I do declare the following to be a clear, exact, and complete description thereof, such as will enable persons skilled in the art to which my invention pertains to make and use the same, reference being had to the accompanying drawing as illustrating some forms in which my invention has been embodied.

The invention is an improvement upon the similar device disclosed in my application filed April 23, 1923, Serial No. 634,144.

The present invention resides in a silencer for the valve tappets of internal combustion engines, and is comprised in a unit in which the elements are assembled. The construction of the said unit is such that when the elements are assembled in their several relations such relations are maintained at all times thereafter. This arrangement permits the handling and placing of the valve silencers without liability to disarrangement of any of its parts.

The device comprises a resilient pressure member adapted for insertion between the adjacent ends of the divided valve rod, and is composed of a plurality of laminated disks which in their normal state are endowed with initial resistance sufficient to maintain the separation of the said ends and hold the valve stem against its actuating tappet.

The end of one of the parts of the divided valve rod is adapted to bear against the outer one of the resilient disks at its center. The disk at the other side of the lamination is adapted to bear upon the rim of a dished member having a circular surface which is convex upon all radial lines. The result of this arrangement permits the resilient lamination to be flexed slightly upon the first application of pressure by the valve stem, but with the increased pressure exerted, the resistance likewise increases by reason of the correspondingly decreasing distance between the points of contact at the opposite sides of the lamination. With the shortened leverage thus created, as the circular line of contact of the lamination with the convex surface takes place, the resistance is increased

until the flexibility of the lamination is absorbed. The thrust of the tappet is then transferred through the valve stem and the interposed cushioning device as one part.

The novel features of my invention will be pointed out in the appended claims.

In the accompanying drawing:

Figure 1 is a vertical sectional view through my improved silencer shown in its normal position interposed between the adjacent ends of the divided valve stem.

Fig. 2 is a similar view showing how the plane of the lamination is distorted under the pressure exerted by the tappet.

Fig. 3 is a vertical section through a modified form of my invention.

In the drawing the numerals 10 and 11 indicate the two aligned parts of a divided valve stem, such valve stem being arranged as usual and operated by the customary tappet mechanism. The numeral 12 indicates an annular body provided upon one of its sides with a recess in which are placed a plurality of laminations 13 and a rigid member 14, the said parts being secured in position in the recess by forming an in-turned flange 15 upon the circular wall surrounding the said recess. In this manner the parts are incorporated into a device having a unitary structure.

The annular member 12 is bored centrally as at 16 so that one of the parts of the valve stem may pass therethrough and bear against one of the plural number of laminations 13. The rigid member 14 is formed as a disk of nonyielding material and is dished in the manner shown so as to provide a circular border or ring which is convex in its cross section, as shown at 17. The arrangement provides a clearance between the bottom of the dish and the lamination. The part 10 of the valve stem is adapted to bear at its end upon the outer side of the dished disk 14, as shown in Figs. 1 and 2. It will be seen that with the parts in normal position the lamination bears at its outer border against the rim of the dish, and that the same may be flexed under a slight pressure exerted upon the part 11 of the valve stem. As the pressure increases the line of circular contact of the lamination with the convex surface becomes of less diameter, thus resisting to a greater degree the increasing pressure exerted upon the valve stem. The operation is illustrated in Fig. 110

- 2, from which it will be seen that the area of circular pressure is reduced to the diameter indicated by the arrows and defined by the vertical dotted lines.
- 5 The resiliency thus provided for in the interposed connection acts effectively to eliminate the tapping noise incident to the operation of valve actuating mechanisms as usually constructed.
- 10 In Fig. 3 I have shown a modification of the construction, but with the use of which the same desirable results are attained. The annular member 12' is threaded in the central bore thereof and is adapted to be received upon the threaded end of one of the sections of the valve rod, whereby the device may be readily adjusted to take up any slack and render its operation more effective. A lock nut 18 on the threaded end of the 15 valve stem will engage the annular body 12' to hold it in the position to which it has been adjusted. One face of the annular part 12' is recessed to receive the lamination 13 in the manner before described, and the bottom 20 of the recess is formed with a circular surface which is convex as at 17' in all cross sections, the laminations shifting their line of circular contact with the convex surface, under pressure exerted by the tappet, in the 25 manner described hereinbefore with reference to the nonyielding disk 14.
- The specific form of the device shown in Fig. 3 is the subject matter of a divisional application filed by me on June 5, 1925, 30 Serial No. 35,185.
- Having thus described my invention, what I claim and desire to secure by Letters Patent of the United States, is:
1. In an internal combustion engine, a 35 divided valve stem, and a cushioning device interposed between the sections thereof, such cushioning device comprising a recessed body and a resilient lamination in such recess, with a rigid circular surface convex in 40 radial section contracting with variable pressure upon one side of the lamination,
- and the contiguous end of one of the valve stem sections upon the other.
2. In an internal combustion engine, a divided valve stem, and a cushioning device 50 interposed between the sections thereof, such device comprising a recessed body and a resilient lamination in the recess, and means for securing the lamination in position, with a rigid circular surface convex in radial section contacting with variable pressure upon one side of the lamination, and the contiguous end of one of the valve stem sections upon the other.
3. In an internal combustion engine, a 55 divided valve stem, and a cushioning device interposed between the sections thereof, such device comprising a recessed body provided with a central bore, a lamination in the recess and a rigid dished disc thereover, the disc having a circular surface convex in radial section, with the contiguous end of one of the sections of the valve stem extending through the bore and contacting with the lamination, and the end of the other 60 section of the valve stem contacting with the outer side of the said disc.
4. A cushioning device for the valve mechanism of an internal combustion engine, such device comprising a body having a 65 recess upon one side, a resilient lamination in the said recess, and a non-yielding disc having a circular surface convex in cross-section adjacent one side of the lamination upon which the lamination is adapted to 70 bear with variable resistance when pressure is exerted upon the other side of the lamination, and means for securing the lamination in the recess.
- In testimony whereof, I have signed my 75 name at Milwaukee, this 15th day of November, 1923.
- J. C. MILLER.
